UNITED STATES PATENT OFFICE.

CHAUNCEY DE VOE, OF NEW YORK, N. Y.

SASH-FASTENER.

1,141,698.

Specification of Letters Patent.

Patented June 1, 1915.

Application filed June 16, 1914. Serial No. 846,408

To all whom it may concern:

Be it known that I, CHAUNCEY DE Voe, a citizen of the United States, and a resident of the city of New York, in the county of Bronx and State of New York, have invented certain new and useful Improvements in Sash-Fasteners, of which the following is a specification.

The present invention relates to improvements in window sash holders, and more particularly to that form which is secured to the upper rail of the lower sash of the window and is adapted to bear or bind against some portion, for instance one of the stiles, 15 of the upper one.

One of the objects of the invention is to provide an improved and simple form of sash fastener which will lock the two sashes together at any desired relative position, so 20 that the window may be left open a sufficient distance for ventilation either at the top or at the bottom, or at both, and prevent the lower sash from being pushed farther upward or the top one from being pulled down 25 to a sufficient extent to enable a person to gain access to the room or house through the window.

Another object of the invention is to provide a device of the character specified which 30 serves to prevent the sashes or either of them from rattling.

A further object of the invention is to produce a sash lock having means which prevent the "picking" of the lock by means 35 of a blade or similar contrivance.

A still further object of the invention is to provide a sash fastener that can be manufactured on a commercial scale, or in other words one which is not so difficult to produce as to be beyond the reasonable cost of 40 such an article.

With these and other objects in view, which will more fully appear as the nature of the invention is better understood, the 45 same consists in the combination, arrangement and construction of parts hereinafter fully described, pointed out in the appended claims and illustrated in the accompanying drawings, it being understood that 50 many changes may be made in the size and proportion of the several parts and details of construction within the scope of the appended claims without departing from the spirit or sacrificing any of the advantages 55 of the invention.

One of the many possible embodiments of

the invention is illustrated in the accompanying drawings, in which:

Figure 1 is a side elevation of the improved fastener, the same being shown in a suitable position relative to the upper and lower sashes of a window, the latter being shown in section; Fig. 2 is a similar view of the fastener and sashes, the fastener being shown in its inoperative position; Fig. 3 is a section taken on line 3-3 of Fig. 1; and Fig. 4 is a plan view of the fastener and the sash to which it is attached.

In the drawings, the upper sash of the window is represented at 10 and the lower sash at 11. To the top of the upper rail of the lower sash is secured by screws, or otherwise, the base plate 12 of the fastener. With this base plate may be made integral or there may be attached thereto in any suitable manner two parallel upwardly projecting frame portions or ears 13, in which is rotatably mounted a spindle 14. To this spindle is rigidly secured, for instance by means of a pin 15, a locking piece or lever 16, that is formed with a cam-shaped end 17, which is adapted to come into contact with the inner surface of the upper sash, for instance with that of one of its stiles, when said lever is in its operative position. The eccentricity of the cam-shaped end of the locking lever increases gradually from the lowermost edge 18 of the lever to its uppermost edge 19, the lower portion 20 of the cam-shaped end of said lever being substantially decreased in thickness, thereby forming a spring-like tail which, when brought into contact with the upper sash, takes a firm grip thereon and effectively prevents a motion of said sash relative to the other one. One end of the spindle 14 projects beyond one of the frame portions or ears 13, and is provided with a shoulder 21, against which is adapted to bear a pawl 22, that is pivoted at 23 to the frame portions 13. This pawl is made in the form of a bellcrank lever, its arm 24 acting as a handle by which the pawl is manipulated and its other arm 25 acting as a lock, having a downwardly projecting lug 26, that is adapted to be brought into engagement with the shoulder 21. In the projecting end of the spindle is furthermore formed a recess 27, in which is adapted to be seated the lug 26 of the pawl to hold the locking lever in its inoperative position (Fig. 2), and thus allowing free movements of both sashes in both directions. The base

- plate 12 is provided with an extension 28, that is of substantially inverted V-shape in cross section, and projects over the plane 29 in which the two sashes of the window meet. 5
- 6 This extension prevents thus effectively the insertion of a blade-like instrument, and guards thereby against lifting the locking lever 16 from outside by means of such instrument. From the extension 28 rise ears 10 30, in which is mounted a roller 31, that is adapted to bear against the upper sash of the window, and serves to prevent the extension 28 from coming into contact with the upper sash. 15
- 16 The operation of this device is as follows: When the locking lever 16 is forced into contact with the upper sash of the window, its springy tail 20 engages with and binds against said sash. If it is attempted to 20 raise the lower sash, it is obvious that the friction between the springy tail 20 of the locking lever and the upper sash will cause a rotation of the locking lever in the direction of the arrow shown in Fig. 1 of the 25 drawings, and will consequently force the said locking lever against the upper sash and bind the two sashes together in direct ratio to the upward pressure owing to the eccentricity of said lever. On the other hand, should it be attempted to lower the 30 upper sash, the same movement of the locking lever will be produced. When it is desired to release the lock, the pawl 22 is disengaged from the shoulder 21 of the spindle 35 14, the locking lever rotated backward, and the lug 26 seated in the recess 27 in said spindle. It is entirely impossible to raise
- the locking lever by means of a blade-like instrument, the extension 28 on the base plate of the device preventing the insertion 40 of such instrument.
- What I claim is:—
1. The combination with the upper and lower sashes of a window, of a locking lever fulcrumed to said lower sash, said locking lever having a cam-shaped end adapted to bear against said upper sash, the lower portion of the cam-shaped end of said lever being substantially decreased in thickness, thereby forming a spring-like tail ending in 50 a knife edge for causing resilient contact between said cam and said upper sash. 45
2. The combination with the upper and lower sashes of a window, of a frame secured to said lower sash, a spindle rotatably mounted in said frame, a lever rigidly secured to said spindle, said lever being provided with a locking cam adapted to bear against said upper sash, a shoulder upon said spindle, said spindle being also provided with a recess, and a pawl having a lug 55 fulcrumed to said frame, said lug being adapted to bear, at will, against said shoulder or to be seated in said recess for holding said cam in locking and unlocking positions, respectively, in relation to said upper sash. 60

Signed at New York, in the county of New York, and State of New York, this 5th day of June, A. D. 1914.

CHAUNCEY DE VOE.
